UNITED STATES PATENTS

3,300,185 1/1967 Metzger 254/134.3

ABSTRACT: The entrance to the socket carried by the upper end of the rod is placed close to one side of the periphery of the pulley and the spring, disposed in the socket, is lifted out and forced around the upper peripheral portion of the pulley by pulling downwardly on the string attached to the lower end of the spring. The string is then released and the weight of the portion of the spring which extends outwardly beyond the other side of the pulley causes the spring to fall downwardly, drawing with it the string. The rope to be installed is then attached to the string and the string is pulled back over the pulley drawing with it the attached rope.

PATENTED NOV 30 1971

DEVICE FOR INSTALLING ROPE ON A FLAGPOLE

This invention relates to a device for installing a rope on a tall, erected flagpole and more particularly to a threading device for pulling a rope to which a flag may be attached over a pulley which is mounted at the top of a flagpole.

BACKGROUND OF THE INVENTION

In the past, in order to install a rope on an already erected flagpole, it has been necessary to remove the pulley and lower it to the ground as shown in U. S. Pat. Nos. 366,141 and 3,124,100, to provide the flagpole with an internal passage for a threading member as shown in U. S. Pat. No. 3,300,185, to build a scaffold to reach the pulley over which the rope passes, to provide expensive lift machinery, to lower the pole to the ground or to climb the pole. These solutions do not provide a simple, inexpensive way for the average person to install a new rope on a flagpole.

SUMMARY OF THE INVENTION

It is an object of this invention to provide a device for installing a rope on a flagpole which may be manipulated by the installer while he stands safely on the ground near the base of the flagpole.

Another object of the invention is to provide a flagpole rope threader which is easy to manipulate for installing a flagpole rope without requiring any particular skill or unusual strength on the part of the installer.

A further object of the invention is to obviate the need for expensive equipment or trained personnel for installing a rope on a flagpole and to eliminate the possibility of accidents associated with climbing or working at elevated positions.

Additional objects of the invention are to provide a device which is rugged, quick and easy to assemble and use, and inexpensive to manufacture.

These and other objects and advantages of the invention will become more apparent from the following specification when considered with the drawings in which:

FIG. 1 is a broken, elevational view of a flagpole showing the rope installing rod in operative position;

FIG. 2 is an enlarged, fragmentary elevational view taken on the line 2-2 of FIG. 1;

FIG. 3 is an enlarged, fragmentary, sectional view of the upper end of the device and the flagpole pulley with the tip end of the device in operative position at one side of the pulley;

FIG. 4 is a view similar to FIG. 3 showing the position of the resilient spring after it has been lifted out of the socket at the upper end of the device and directed over the pulley, the major portion of the spring hanging freely downwardly after having passed over the pulley and with the rear portion of the spring still resting on the pulley; and

FIG. 5 is an enlarged, sectional view taken on the lines 5-5 of FIG. 3 showing the guide bracket fixed on the installing rod and frictionally embracing the flagpole.

For purposes of illustration, a flagpole 1 of conventional construction is shown having a ball 3 fixed on its upper end and a pulley assembly 5 mounted on the pole a short distance below the ball 3.

The pulley assembly 5 includes a sheave or pulley 7 rotatably mounted on the body portion of a threaded bolt 9 which passes through a suitable opening formed in the flagpole. A pulley guard or protector 11 is disposed over the upper peripheral portion of the pulley 7 and is secured to the flagpole by screw fastening means 13 and the nut 9a fixed on the threaded end of bolt 9. The guard 11 forms a tunnel or passageway 15 with the upper peripheral portion of the groove of the pulley 7.

The rope installing device of this invention comprises an elongated rod 17 which is of sufficient length to reach the flagpole pulley while being held by the user standing adjacent the base of the pole. The rod may be formed in one piece, if desired, but, for convenience in handling, transportation and

storing, it is preferred that the rod include a plurality of sections 19 of suitable length which may be assembled to provide a rod of the required length for reaching the pulley and which may be readily disassembled.

5 The rod 17 may be either solid or tubular and formed of strong, lightweight material such as plastic, aluminum or wood. As shown by way of example, the sections 19 of the rod 17 are slightly tapered and tubular and provided at their forward end with a socket 21 which may have a metal lining 23 and at their rearward end with a plug portion 25 which may have a metal sleeve 27 on its outer surface. Obviously, the sections of the rod could be joined by other types of joints or the rod could be constructed so as to telescope in the manner of a fishing pole.

10 15 The tip section 29 of the rod 17 is provided at the rearward end thereof with a plug portion 25 having a metal sleeve 27 thereon, and is provided at the forward end thereof with an elongated socket or cavity 31 which extends inwardly from the outermost end 33 of the tip to a bottom wall 35.

20 25 A resilient spring 37, shown for illustrative purposes as being spirally wound, is removable disposed in the cavity 31 with its bottom end seated on the wall 35 and with its top end disposed adjacent the entrance to the cavity 31. The outer diameter of the spring 37 is sufficiently smaller than the internal diameter of the cavity 31 so that the spring may slide freely in and out of the cavity.

25 30 A lightweight string 39 is fastened to the bottom end 41 of the spring 37 and extends upwardly in the cavity 31 beside the spring 37 and passes out of the cavity adjacent the upper end thereof through a small opening 43 formed in the wall of the tip portion 29 closely adjacent the upper end thereof. The string extends downwardly from the opening 43 to adjacent the lower end of the rod 17 for manual manipulation by the 35 person installing the rope.

35 40 Since the upper end of the tip section 29 of the rod 17 is to be disposed at one side of the pulley 7 and at the entrance 45 of the tunnel 15 when the device is in operative position, a resilient attachment bracket 47 is provided for assisting in guiding and maintaining the upper end 33 of the tip 29 in alignment with the pulley groove 49 at the entrance to the guard 11. The attachment bracket 47, formed of resilient or spring material, comprises a pair of resilient members 51 and 53 which are formed at one end to fit closely around the rod 17 and are adjustably fixed thereto by threaded fasteners 55. The outer free end of the members 51 and 53 are of arcuate configuration and provide therebetween a generally circular opening for frictionally engaging the outer periphery of the flagpole. The free ends of the members 51 and 53 flex sufficiently for readily permitting the bracket to be attached and removed from a flagpole.

45 50 55 In operation, the tip section 29 with the resilient spring 37 and string 39 in position as shown in FIG. 3, is assembled with the number of rod sections 19 required to reach the flagpole pulley from the ground. With the rod 17 disposed in a vertical position, the attachment bracket 47 is engaged with the flagpole 1 in the position shown in FIG. 5 and the rod 17 and bracket 47 are adjusted along the flagpole to position the end 33 of the cavity 31 at the side of the pulley 7 and at the entrance 45 of the tunnel 15. With the device in this position, the resilient spring 37 is lifted out of the cavity 31 and is forced through the tunnel 15 and around the periphery of the pulley 7 by pulling on the string 39. The major portion of the long, 60 65 resilient spring 37 will pass over the upper peripheral portion of the pulley 7 and out of the tunnel exit 57 and will hang freely downwardly as shown at 59 in FIG. 4. The string 39 is then released and the weight of the portion of the spring 37 which extends out of the tunnel exit 57 and hangs freely downwardly 70 as at 59 will cause the spring to fall by gravity, drawing the rear portion thereof over the pulley 7 and pulling with it the string 39 which is attached to the bottom end of the spring.

70 After the spring 37 reaches the ground, the spring 37 is removed and the end of the rope to be installed is attached to the end of the string 39. The string 39 may then be pulled back

up over the pulley 7 carrying with it the flagpole rope which will be pulled up over the pulley 7 and downwardly to adjacent the bottom end of the flagpole.

Preferably the resilient spring 37 is of substantial length, for example, about two feet long and of relatively small diameter, for example, about three eighths of an inch. The size of the wire from which the spring 37 is closely wound is of small diameter, for example, about 0.035 inch so that the spring is extremely flexible and readily bent into the small arc required to pass over a pulley of relatively small diameter. Obviously, the resilient spring could also be in the form of a straight piece of spring material or of some other suitable configuration and could be provided at its outer free end with a suitable weight to assist in pulling the rear portion thereof over the pulley after the major portion of the spring has been lifted out of its cavity. Regardless of the type of spring which is employed, the spring is constructed and arranged so that the portion thereof which passes over the pulley and hangs freely downwardly when the string is pulled to raise the bottom end of the spring in the cavity to about opposite the small string opening 43, has sufficient weight to drag the remaining portion thereof over the pulley so as to permit the spring to fall to the ground when the string is released. It is also contemplated that the socket or cavity be adjustably secured to the upper end of the rod at one side thereof, that is the axis of the tip section would not be in axial alignment with the axis of the rod. Thus the tip would be mounted on the rod for angular adjustment relative thereto so as to reach pulleys located in remote or relatively inaccessible locations.

It is to be understood that the form of my invention, herewith shown and described, is to be taken as a preferred example of the same and that various changes in shape, size, and arrangement of parts may be resorted to without departing from the spirit of my invention or the scope of the appended claims.

What I claim is:

1. A device for installing a rope on a flagpole which has a pulley rotatably mounted adjacent the upper end thereof and a stationary guard fixed a short distance above the upper peripheral portion of the pulley, said guard forming with said pulley a tunnel having an entrance and an exit, said device comprising:

an elongated rod having a length sufficient to reach said pulley when held manually in a generally vertical position from a location disposed a substantial distance below the pulley;

an elongated socket having an open upper end and a wall closing the lower end thereof carried by the rod adjacent its upper end with the axis of the socket extending generally in the direction of the axis of the rod;

50

an elongated, flexible, resilient spring removably disposed in the socket with its lower end resting on said wall and with its upper end disposed adjacent the open end of the socket;

and a string fixed at one end to the lower end of the spring and extending upwardly in the socket and then out of the socket adjacent the upper end thereof and then downwardly to adjacent the lower end of the rod, whereby by positioning the open end of the socket closely adjacent said one side of the pulley and at the entrance of said tunnel and pulling downwardly on the string, the spring will be lifted out of the socket and the greater portion of it will pass over the pulley and through said tunnel and will extend a substantial distance outwardly of the tunnel exit at said other side of the pulley, and the weight of the portion of the spring extending out of the tunnel exit will, upon release of the string, cause the spring to fall by gravity to adjacent the bottom of the pole pulling with it the string whereupon the rope is installed by attaching one end of it to the end of the string or the spring and by pulling downwardly on the string, the string will be pulled back over the pulley and the rope drawn thereby upwardly over the pulley and downwardly to adjacent the bottom of the pole.

2. A device according to claim 1 in which the socket is formed in the upper end of the rod with the socket opening disposed at the extreme upper tip thereof, and the axis of the socket opening is coaxial with the axis of the rod.

3. A device according to claim 1 in which the wall of the socket is formed adjacent the open end thereof with a small string guide opening having a relatively smooth wall.

4. A device according to claim 1 in which the spring comprises a length of spirally wound spring wire.

5. A device according to claim 1 in which a guide bracket for engaging the pole and guiding the upper end of the rod is fixed to the rod adjacent to but spaced from the upper end thereof.

6. A device according to claim 5 in which the guide bracket comprises a pair of resilient members, means fixedly securing one end of the members together and to the rod, the other end of the resilient members being free and unattached and normally spaced a short distance apart, and the midportion of the members being of arcuate configuration providing therebetween a generally circular opening for frictionally engaging the pole after it passes between the free ends of the members.

7. A device according to claim 1 in which the rod comprises a plurality of sections including a tip section having said socket opening therein, and means securing said sections together in end-to-end relationship.
